UNITED STATES PATENT OFFICE.

ROBERT DON SPARKS, OF CHICKASHA, OKLAHOMA.

GOLF-GREEN CUP.

Application filed October 30, 1922. Serial No. 597,995.

To all whom it may concern:

Be it known that I, ROBERT DON SPARKS, a citizen of the United States, residing at Chickasha, in the county of Grady and 5 State of Oklahoma, have invented certain new and useful Improvements in Golf-Green Cups, of which the following is a specification.

This invention relates to cups for use on 10 golf greens and particularly on sand greens.

The main objects of the invention are to facilitate the removal of sand, which may drift into and accumulate in the cup, particularly in windy weather; to improve the 15 construction of the flag-staff so as to secure accurate engagement with and convenient removal from the cup; and to secure rigid mounting of the cup in the soil, so that it may neither settle nor work loose under 20 the thrashing of the flag-staff in heavy winds.

To secure these and other incidental desirable results, I have combined the following features. I make the cup somewhat 25 deeper than usual and fix to it one or more external horizontally extending flanges or plates. These flanges or plates give sufficient bearing surface in the soil to prevent settling or working of the cup in the soil. 30 Within the main cup, above described, I insert a removable auxiliary cup which fits closely within the main cup, and which may be retained or latched in the main cup so as ordinarily to be fixed in place through 35 capable of quick removal for the purpose of emptying sand. The latching mechanism is mounted in a central housing projecting upward from the bottom of the inner cup, making the latch mechanism accessible for 40 manipulation and avoiding openings at the bottom of the auxiliary cup through which sand might work.

The flag-staff is carried by a circular base which fits closely within the auxiliary 45 cup and has projecting fingers which extend to the bottom of the auxiliary cup around the central latch housing. Since these fingers are in contact for a considerable distance with the sides of the cup, this 50 secures a staff base which though closely confined by the cup when in place, may yet be freely withdrawn. The parts are so proportioned that the top of the flag-staff base is sufficiently below the rim of the 55 cup to allow balls to be holed while the staff is in place.

The extra depth of the main cup serves several useful purposes beside increasing the stability of the main cup. It offers space for the latch housing, and greater capacity 60 for the harmless accumulation of sand, and makes it possible to ensure accurate and rigid alinement of the flag-staff base.

A structure conforming to the above description has proved peculiarly satisfactory 65 in actual use and is illustrated in the accompanying drawings, in which:—

Fig. 1 is a longitudinal vertical section of the complete device, the ground level being indicated in broken lines. 70

Fig. 2 is a side elevation showing the cup with a cap applied and covered with clay or soil, an arrangement adopted when the hole is not in use.

Fig. 3 is an enlarged fragmentary plan 75 view of the latch.

Fig. 4 is a perspective view of the flag-staff base.

Fig. 5 is a perspective view of the removable cup, a portion being shown broken 80 away to disclose the arrangement of the latch housing.

The body of the cup consists of a cylindrical shell 11 flanged at its bottom and connected by rivets 12 passing through such 85 flange to a base plate 13 of substantial area. At about mid-height of the shell 11 is a flange or plate 14 riveted at 15 to shell 11 and having at its periphery a downward and outward flaring skirt 16. The plate 14 and 90 skirt 16 are preferably of circular contour and serve together with plate 13 to prevent settling of the cup structure and to give it lateral stability. In some cases it is desirable that the base plate 13 and the stabilizing plate 14 be removable from the shell 11, and in such cases I may substitute for the rivets 12 and 15, above referred to, small 95 bolts or machine screws, as is obvious. These separable connections are sometimes 100 of convenience in mounting the cup in the green. Modifications of form and in the modes of connecting the parts together are obviously possible.

Fitting closely, but freely within shell 11 is an auxiliary cup 17 preferably of light sheet metal, and terminating at or slightly below the upper rim of the shell 11. Except for a small central aperture 18 the cup 17 is closed at its bottom, and surrounding 110 the opening 18 and riveted or otherwise connected to cup 17 is an upstanding conical

shell or housing 19 having at its top an opening 20 axially aligned with opening 18. Consequently there is at the bottom of the cup 17 a relatively deep pocket surrounding 5 housing 19 and offering a place for the accumulation of sand without the possibility of any leakage therefrom.

Longitudinally slidable in the openings 18 and 20 is the latch rod 21 having the 10 finger piece 22 (shown as a loop) above the top of housing 19 and the spring seat 23 within the housing 19. Surrounding rod 21 and below spring seat 23 is a coil spring 24 which seats at its upper end against the 15 lower side of seat 23 and at its lower end against a washer 25 surrounding rod 21 and resting on the bottom of cup 17. The rod 21 carries at its lower end a cross-arm 25, which when properly positioned may 20 pass through a slot 26 in plate 13.

To latch the cup 17 in shell 11 the cup is introduced into the shell, and the rod 21 is turned by finger piece 22 until cross-arm 25 enters slot 26. Finger piece 22 is then 25 pushed downward compressing spring 24 and causing cross-arm 25 to pass through slot 26 until it is wholly below plate 13. Rod 21 is then rotated in either direction about a quarter turn and released. The parts are 30 so proportioned that the spring 24 will now act to hold the cup 17 tightly against plate 13. It is desirable, but not essential, so to proportion the parts that in the highest position of rod 21, cross-arm 25 projects far 35 enough below the bottom of cup 17 to engage the top face of plate 13, as this facilitates alining cross-arm 25 with slot 26 by feel.

The base for the flag-staff consists of a 40 circular casting 30 having an upward extending peripheral flange 31 and several downward projecting fingers 32 curved inward at their lower ends as shown at 33. A tube 34 screwed into the central boss 35 offers means to receive the wooden staff 36 held by a rivet or pin 37.

The flange 31 and fingers 32 serve to hold 45 the base, and hence the staff, upright and the inward curvature of the fingers at 33 guides the entering movement of the base. The flag-staff base when in place straddles the housing 19, and yet because of the depth of sleeve 11 and cup 17 leaves space above it to receive balls which may be holed while the 50 base is in the cup.

The base 30, because of its circular flange, 55 will catch such small quantities of sand as drift into the cup under ordinary conditions between successive matches. Hence, by 60 dumping the base each time the flag is withdrawn, the frequency with which the auxiliary cup must be withdrawn and emptied can be greatly reduced.

What is claimed is:—

65 1. A cup for golf greens, comprising in

combination a cup-like shell; and a horizontally extending plate rigidly connected with said shell extending a substantial distance from the periphery thereof and so located as to be embedded in the earth when said cup is 70 in position in a green.

2. A cup for golf greens, comprising in combination a cup-like shell; and a plurality of outward extending stabilizing members rigidly connected with said shell extending 75 a substantial distance from the periphery thereof and so positioned as to be embedded in the earth when said cup is in position in a green.

3. A cup for golf greens, comprising in 80 combination a cup-like shell; and a plurality of horizontally extending flanges rigidly connected with said shell and so positioned as to be embedded in the earth when said cup is in position in a green, one of said 85 plates extending a substantial distance from the periphery of said shell and having a flange-like skirt.

4. A cup for golf greens, comprising in combination a main cup; an auxiliary cup 90 closely fitting within said main cup and removable therefrom; a releasable latch operable to connect said auxiliary cup with said main cup; and a resilient member associated with said latch and arranged to permit limited relative movement of said cups while said latch is engaged.

5. A cup for golf greens, comprising in combination a main cup; an auxiliary cup 100 closely fitting within said main cup and removable therefrom; a housing mounted on the bottom of auxiliary cup and extending upward within the same; and a locking mechanism mounted in said housing, accessible for manipulation at the upper end 105 thereof and operable to engage a portion of said main cup and thereby lock said auxiliary cup in place.

6. A cup for golf greens, comprising in combination a main cup; an auxiliary cup 110 closely fitting within said main cup and removable therefrom; a housing mounted on the bottom of auxiliary cup and extending upward within the same; a locking mechanism mounted in said housing, accessible 115 for manipulation at the upper end thereof and operable to engage a portion of said main cup and thereby lock said auxiliary cup in place; and a flag-staff base closely but removably fitting within said auxiliary cup 120 and having a portion which surrounds said housing.

7. A cup for golf greens, comprising in combination a cup-like main shell having laterally extending earth engaging projections below its top; an auxiliary cup closely fitting within said main shell and removable therefrom; a housing mounted on the bottom of said auxiliary cup and extending upward within the same; a locking mecha- 130

nism mounted in said housing, accessible for manipulation at the upper end thereof and operable to engage a portion of said main shell and thereby retain said auxiliary cup in place; and a flag-staff base closely but removably fitting within said auxiliary cup and having a portion which surrounds said housing.

8. The combination with a sand green of
10 a main cup set with its rim below the level of

the green; an auxiliary cup removably mounted in the main cup; and a cover closing the top of said main cup and buried beneath the surface of the green, the parts being so arranged that such cup is complete but out of play, without interfering with play on the green. 15

In testimony whereof I have signed my name to this specification.

ROBERT DON SPARKS.
